HEAVY DUTY SCRAPER

Max M. Brodersen, Alhambra, and Len O. Bird,
Glendale, Calif.; said Brodersen assignor to
said Bird

Application March 25, 1935, Serial No. 12,812

6 Claims. (Cl. 37—126)

This invention relates generally to scrapers which are used for removing dirt, sand, and other material, as in the leveling of ground, building roads, excavating, grading, etc., and more particularly to the type known as heavy duty, carry all, scrapers, by means of which large amounts of dirt may be removed.

Of the manifold objects of this invention, the principal one is to provide a heavy duty scraper comprising a jointed frame structure which is supported at the forward and rearward ends on wheeled carriages and carries, pivotally supported therein, a scraper bowl and an apron which is adapted to serve as a closure for the receiving

10 side of the bowl and is designed to pickup and retain about one-third of the total load capacity of the scraper.

Another object is the provision of an implement in which power means, either cable or hydraulic, are provided for imparting a knee action to the jointed frame structure for raising and lowering the implement and for imparting oscillating motion to the pivoted bowl and apron thereby selectively controlling the scraping, loading, carrying, and dumping, positions of said bowl and apron.

This construction permits a large amount of dirt to be scraped and carried with but a relatively small expenditure of power, since the main factor which limits the size of the ordinary single-scoop scraper for practical purposes is the great frictional resistance offered to the loading of the dirt when the latter has to pile up on itself and move back by the pressure of the incoming dirt.

In operating the present implement, the bowl is moved along the ground surface until a substantial amount of dirt is accumulated ahead of the bowl after it has been loaded to capacity, the apron is then released and permitted to drop on top of the accumulated dirt. The resistance offered by the heaped up dirt prevents the apron from closing off entirely the receiving side of the bowl and further movement of the implement forces additional dirt up through the remaining opening. When the scraper is filled to capacity the implement is elevated and the weight of the dirt upon the apron together with the weight of the apron itself closes the receiving side of the bowl completely. To discharge the dirt the bowl and the apron are swung away from each other on the order of the clam-shell bucket.

As a further object, it provides a simple and compact yet substantial power controlled implement by means of which large quantities of earth

may be removed, transported, and discharged quickly and efficiently with a minimum of power.

With these and other objects in view the invention consists in the combination, correlation, and construction, of parts, members, and features, which will be described in the specification and will be finally pointed out in the claims.

Referring to the drawings:

Figure 1 is a plan view of a device embodying our invention.

Figure 2 is a side elevation of Figure 1.

Figure 3 is an end elevation of Figure 2.

Figure 4 is a section taken approximately on line 4—4 of Figure 1.

Figure 5 is a side elevation of the implement 15 illustrating the cable arrangement for controlling the bowl and apron and showing the bowl and apron in the load carrying position.

Figure 6 is a side elevation similar to Figure 5 in which the bowl and apron are shown in the 20 load dumping position.

Figure 7 is a side elevation of the implement illustrating the cable arrangement for raising and lowering the implement and showing same in the lowered position.

Figure 8 is a side elevation similar to Figure 7 in which the implement is shown in the raised position.

Figure 9 is a detail of the bowl stop and detent.

Figure 10 is a plan view of another modified form of the invention.

Figure 11 is a side elevation of Figure 10.

Figure 12 is a rear end view of Figure 11.

The objects outlined above are attained by the 35 preferred and modified forms of embodiment of the invention shown in the drawings, which in a generic sense consists of a jointed frame structure comprising forward and rearward sections, wheeled supports for the forward and rearward 40 ends of said frame structure, a bowl and a closure for same pivotally associated with the rear section of said frame, means for imparting a knee action to said frame structure for raising and lowering the implement and means for controlling the scraping, loading, carrying, and discharging, positions of the bowl and its closure.

Referring to Figures 1 to 9 inclusive.

In a more specific sense, the preferred form of heavy duty scraper exemplified in the accompanying drawings in a practical form of embodiment, is shown as comprising a jointed frame structure 50 which includes the forward and rearward sections 2 and 3, respectively. The forward section 2 of the frame 1 consists of the transverse mem- 55

ber 4 which is provided with the centrally located leg 5 which in turn is swivelably connected, as at 6, to the wheeled carriage 7. The wheeled carriage 7 is equipped with the draft tongue 8, which is adapted in the usual manner for connection to a tractor. At the ends of the transverse member 4 are the rearwardly extending arms 9 having at the rearward ends the vertical members 10 which are reinforced by means of the angle brace members 11. The vertical members 10 carry at the upper ends the cross member 12 to which is secured a block of three pulleys indicated at 13.

The rear section 3 of the frame 1 consists of the forwardly extending arms 14 which are pivotally supported at their rear ends on the axle 15 of the wheeled carriage 16, as shown at 17. Just ahead of the wheeled carriage 16 and interposed between the arms 14 is the transverse tie member 18. The forward ends of the arms 14 are provided with the vertical members 19 which are reinforced by means of the angle brace members 20.

The forward and rearward sections 2 and 3, respectively, of the frame 1 are pivotally connected as at 21.

25 A scraper bowl 22 is pivotally carried on the rear section 3 of the frame 1, as shown at 23. Secured to the upper edge of the rear side of the bowl 22 is a block of two pulleys, as shown at 24.

Disposed forwardly of the receiving side of bowl 22 to serve as a closure for same, is the apron 25 which has the rearwardly extending arms 26 connected, as at 27, to the angle braces 20 on the rear section 3 of the frame 1. Secured to the forward side of apron 25 is a block of two pulleys, as shown at 28.

30 Connected to the pivots 23 which support the bowl 22 on the rear section 3 of frame 1 are the actuating arms 29. The arms 29 are forked as at 30 to straddle the rearwardly extending arms 9 of the section 2. The forked ends 30 of the arms 29 are conjoined by means of the transverse member 31. The forked ends 30 of the arms 29 are provided with the forwardly extending ears 32 which carry, pivotally secured thereon, the flanged 45 wheels 33 which in turn are adapted to ride on the arms 9 of the frame section 2. A block of five pulleys is secured on the transverse member 31, as indicated at 34.

50 Mounted on the leg 5 of the forward frame section 2 is a bracket 35 which carries a block of four pulleys as indicated at 36.

Referring to Figures 5 and 6 which show the cable arrangement for controlling the scraping, loading, carrying, and discharging positions of the bowl 22 and apron 25:

55 The end of the cable 37, ordinarily known as the dead end, is secured to the back of bowl 22 as shown at 38 and the cable is reaved through the pulley blocks 24 and 13 to effect a block and tackle arrangement for tilting the bowl 22 about its pivots 23. The cable 37 is also reaved through pulley blocks 28 and 34, to effect a block and tackle arrangement for raising and lowering the apron 25, and is passed over a pulley in the block 36 then 60 through the swiveled pulley 39 to be connected to a drum or reel of any conventional winding apparatus associated with the power take-off of a tractor.

65 By pulling and releasing cable 37 the bowl 22 and apron 25 are actuated in proper sequence relative to each other, for scraping, loading, carrying, and dumping, by virtue of the difference in their respective weight, thus it is necessary to have only one control for both the apron and the bowl.

70 When the implement is in the carrying position

as shown in Figure 5 and it is desired to discharge the load, cable 37 is pulled, raising first the apron 25 inasmuch as it is lighter in weight than the bowl, and discharging part of the load. After the apron has reached its limit of travel the bowl 22 is tilted forward discharging the remaining load, as shown in Figure 6.

75 For resetting the bowl 22 to its scraping position the cable 37 is gradually released until the stops 40 at the back of bowl 22 come to rest on the transverse member 18. The bowl 22 returns to the scraping position before the apron 25 is lowered by virtue of its much greater weight. After the bowl is reset the apron may be held in its raised position by stopping the releasing of cable 37. This position is illustrated in Figure 2.

80 The bowl 22 may be retained in the scraping position, securely enough for all practical purposes, by means of the spring loaded detent 41, which comprises a bolt 42 slidably supported in brackets 43 and 44 secured on the transverse member 18. The bolt 42 carries at one end the roller 45 which cooperates with the detent cam 46 on the bowl 22. Interposed between the bracket 44 and shoulder 47 on the bolt 42 is the spring 48. See Figure 9.

85 Referring to Figures 7 and 8 which show the cable arrangement for controlling the operative and inoperative positions of the implement:

90 The dead end of cable 49 is connected to the bracket 35, as shown at 50. The cable 49 is reaved through the respective pulley blocks 36 and 34 on the bracket 35 and the transverse member 31 which connects the actuating arms 29, and is passed over one of the pulleys in block 13, under 95 a pulley in block 34, over a pulley in block 36 and then through swiveled pulley 51 to be connected to a drum or reel of any conventional winding device on the tractor.

95 To raise the implement from the lowered position in Figure 7 to the elevated position in Figure 8, the cable 49 is pulled to effect a block and tackle action between pulley blocks 36 and 34, consequently imparting a pulling action to the actuating arms 29 which in turn draw the rear frame section 3 forwardly causing the frame structure 1 to buckle upward about the pivot joints 21 in a manner similar to bending a knee, thereby elevating the bowl 22.

100 A stop 52 for the wheels 33 is positioned on the arms 9 of frame section 2 to limit the forward movement of actuating arms 29 and consequently the raising movement of the implement.

105 Upon releasing the cable 49 the knee action of frame structure 1 is reversed thereby lowering 55 the bowl 22.

110 In Figures 10 to 12 inclusive, a modified form of the implement is shown in which hydraulic means are provided for controlling the scraping, loading, carrying, and discharging positions of the bowl and apron, and the operative and inoperative 105 positions of the implement.

115 The jointed frame structure 1b consists of the forward section 2b and the rearward section 3b. The forward section 2b comprises a transverse member 61 which is provided with the centrally located leg 62, supported on the wheeled carriage 7b, in the manner shown and described in the preceding, preferred, and modified forms. The transverse member 61 is provided at the ends with 120 the rearwardly and downwardly extending arms 63.

125 The rear section 3b consists of the forwardly extending arms 64 carrying the diagonal members 65 which extend upwardly as well as forwardly 75

and are connected at the ends to the cross member 66. The arms 64 and members 65 are reinforced by means of the vertical and diagonal bracing members 66' and 67, respectively. The rear ends of the arms 64 are associated through the resilient means 68 with the axle 69 of the wheeled carriage 16b, which in turn is pivoted transversely, as shown at 70 on the bracket 71 which extends rearwardly from the cross member 12, connecting the arms 64 and located just ahead of the wheeled carriage 16b.

The bowl 22b is pivotally mounted by means of trunnions 73 on the rear section 3b of the frame 1b. The rear ends of arms 63 on the forward frame section 2b are pivotally connected to the trunnions 73. The apron 25b is provided with the rearwardly extending arms 26b which are pivotally connected, as at 27b, on the diagonal member 65.

20 The resilient suspension means 68 consist of springs 74 interposed between the top of axle 69 and suitable retaining caps 75 bolted to the arms 64. Slots 76 provide the necessary clearance for axle 69 for vertical movement of same.

25 By pivotally supporting the rear end of the implement on the carriage 16b for transverse oscillatory movement of said carriage relative to the implement, a load may be carried in a substantially level position when traversing an uneven 30 surface.

30 A hydraulic cylinder 77 is pivotally mounted in bracket 78 on the cross member 66 and has the piston rod 79 pivotally connected, as at 80, to the back of bowl 22b, for controlling the tilting of 35 the bowl.

35 A hydraulic cylinder 81 is pivotally mounted in bracket 82 on the cross member 66 and has the piston rod 83 pivotally connected, as at 84, to the apron 25b, for controlling the opening and closing 40 of the receiving side of bowl 22b.

45 A hydraulic cylinder 85 is pivotally mounted in bracket 86 of the leg 62 of the forward frame section 2b and has the piston rod 87 pivotally connected, as at 88, to the bracket 89 on the cross member 66 of the rear frame section 3b, to impart a knee action to the jointed frame 1b for controlling the operative and inoperative positions 50 of the implement.

Having thus described our invention, we claim:

50 1. In a dirt moving machine a front frame structure having opposite side elements, a front running gear unit supporting the forward end of said frame structure, a rear frame structure pivotally connected at its lower forward end to the rear of said front frame structure for vertical movement, said rear frame structure having opposite side members, a rear running gear supporting the rear ends of said rear frame structure, means associated with said frame structures to control pivotal movement with relation to each other around their common pivotal axis, whereby the level of said axis may be raised and lowered, a scraper bowl disposed between the said frame elements of the rear frame section and mounted 55 for vertical swinging movement upon said rear frame section and upon its pivotal connection with the front frame section, stop means carried by the rear frame section for limiting the downward swinging movement of the rear of the bowl, and means for swinging the bowl vertically to desired positions of angularity with relation to the ground.

2. In a dirt moving machine a front frame structure having opposite side elements, a front running gear unit supporting the forward end of

said frame structure, a rear frame structure pivotally connected at its lower forward end to the rear of said front frame structure for vertical movement, said rear frame structure having opposite side members, a rear running gear supporting the rear ends of said rear frame structure, means associated with said frame structures to control pivotal movement with relation to each other around their common pivotal axis, whereby the level of said axis may be raised and lowered, a scraper bowl disposed between the said frame elements of the rear frame section and mounted for vertical swinging movement upon said rear frame section and upon its pivotal connection with the front frame section, stop means carried by the rear frame section for limiting the downward swinging movement of the rear of the bowl, means for swinging the bowl vertically to desired positions of angularity with relation to the ground, a front gate for the bowl pivotally carried upon the rear frame section whereby said gate may move toward and away from an obstructing position with relation to the throat of the bowl, and independent operating means for said gate.

3. A power scraper comprising a front running gear unit, a rear running gear unit, a front frame section supported at its forward end upon the front running gear unit, a rear frame section supported at its rear end upon the rear running gear unit and a common articulate connection between the lower forward end of the rear frame section and the rear of the front frame whereby the sections may assume desired angular relation to each other and the horizontal whereby the forward end of the rear frame section may be raised and lowered, a scraper bowl pivotally connected at its sides and adjacent its forward end to the articulate connection of the rear frame section, stop means limiting the downward swinging movement of the rear of the bowl, and positively operable means for swinging the rear of the bowl upwardly to different positions of angularity.

4. A power scraper comprising a front running gear unit, a rear running gear unit, a front frame section supported at its forward end upon the front running gear unit, a rear frame section supported at its rear end upon the rear running gear unit and an articulate connection between the front and rear frame sections whereby the sections may assume desired angular relation to each other and the horizontal whereby the forward end of the rear frame section may be raised and lowered, and control means for positively actuating said sections, a scraper bowl pivotally connected at its sides and adjacent its forward end to the articulate connection of the rear frame section and the front frame section, stop means limiting the downward swinging movement of the rear of the bowl, and positively operable means for swinging the rear of the bowl upwardly to different positions of angularity, a front gate for the bowl, arms therefor extending horizontally above the bowl, and means pivotally connecting the rear ends of said arms with the rear frame.

5. A power scraper comprising a front running gear section, a substantially U-shaped lifting yoke, the arms of which extend rearwardly of the transverse portion and which is supported upon the front running gear unit, a rear running gear unit, a lifting frame comprising a pair of side rails supported from the rear running gear unit, the forward ends of the side rails and the rearwardly extending arms of the lifting yoke being articulately connected for vertical movement whereby the supported ends of the lifting yoke

and lifting frame may swing vertically with the supporting running gear units and the intermediate pivotal portion will assume desired spaced relations to the ground, operating means whereby said lifting yoke and lifting frame may be moved with relation to each other to different positions of angular adjustment, a scraper bowl carried by the lifting frame disposed between the side members thereof and pivoted for vertical swinging movement independently thereof, means for pivotally swinging said bowl, a front gate for the bowl adapted to swing toward and away from an obstructing position with relation to the bowl, arms for the front gate extending over the bowl and being pivotally mounted upon the rear frame upon an axis adjacent the rear of the bowl and independently acting means for raising and lowering the gate.

6. A power scraper comprising a front running gear unit, a rear running gear unit, a front frame

section supported at its front end upon the front running gear unit, a rear frame section supported at its rear end upon the rear running gear unit, an articulate connection between the front and rear frame sections, a scraper bowl pivotally connected at its sides and adjacent its forward end to the articulate connection between the rear frame section and the front frame section, lock means positively engaging the bowl to eliminate the downward movement thereof, a front gate for the bowl, arms therefor extending horizontally above the bowl and means pivotally connecting the rear end of said arms with the rear frame and means positively operable for swinging the bowl about its pivot and control means for positively actuating the front end and rear frame sections. 5 10 15
